AIR DISTRIBUTION UNIT

Walter W. Kennedy, Rockford, Ill., assignor to
Barber-Colman Company, Rockford, Ill., a cor-
poration of Illinois

Application April 12, 1946, Serial No. 661,788

6 Claims. (Cl. 98—40)

1

This invention relates to outlets for distributing air into compartments or rooms from overhead supply ducts.

One object is to provide a novel overhead distribution outlet particularly adapted for introducing substantial volumes of air into low-ceiling rooms such as railway cars, while distributing the air over a wide area without subjecting the room occupants to objectionable drafts.

Another object is to provide a novel air distribution unit adapted to be mounted adjacent a room ceiling and having a peripheral outlet for directing air laterally along a ceiling and a central outlet for directing a plurality of separated air streams downwardly along and outwardly from the outlet axis.

A further object is to impart a swirling action to the discharged air so as to effect a looping together of the air streams from the central and peripheral outlets and thereby provide for quick dissipation of the energy of the moving air body.

The invention also resides in the novel construction of the central air outlet and the swirl producing means.

Other objects and advantages of the invention will become apparent from the following detailed description taken in connection with the accompanying drawings, in which

Figure 1 is a diagrammatic view showing the improved air distribution unit mounted in the ceiling of a streetcar.

Fig. 2 is a bottom view of the improved unit.

Fig. 3 is a diametrical sectional view.

Fig. 4 is a view similar to Fig. 3, showing a modified form of the swirl producing means.

Fig. 5 is a sectional view taken along the line 5—5 of Fig. 4.

The improved distribution unit shown in the drawings for purposes of illustration is intended to be mounted in the ceiling of a room or compartment 10 so as to provide a peripheral outlet 11 immediately below the ceiling 12. The outer wall 14 of this outlet is defined by a tubular shell 13 projecting upwardly through a hole in the ceiling and telescoping with a duct 15 to which the air to be distributed is delivered under pressure. Herein, the shell is secured by screws 17 to a frame 18 disposed above the ceiling.

The lower end of the shell flares outwardly to form the wall 14 and terminates in an upwardly turned flange 19 projecting through the ceiling. The inner wall 20 of the peripheral outlet 11 is defined in this instance by a generally flat deflector ring 21 which is disposed substantially horizontally and supported from the shell 13 by an-

2

nularly spaced straps 22. The outside diameter of the ring 21 is only slightly larger than the internal diameter of the shell so that the ring intercepts the outer portion of the advancing air body and diverts the same laterally and outwardly between the surfaces 14 and 20 defining the outlet 11. These surfaces are shaped so that the peripheral stream is directed downwardly at a small angle.

10 The internal diameter of the ring 21 which is substantially less than that of the shell 13 defines a central opening 25 having means disposed therein for intercepting the downwardly moving air body and dividing it into a plurality of separate 15 streams 26 which diverge relative to each other both radially and downwardly. Herein, the intercepting means comprises a plurality of grilles 27, preferably six, and of equal size, in the form of sectors, each of which is composed of a multiplicity of closely spaced parallel flat fins 28 lying on chords of the circular central opening 25. Each fin is inclined at an angle of approximately 45 degrees relative to the outlet axis with its upper surface inclined downwardly and outwardly 20 relative to the axis of the opening 25. The fins of each sector are connected by crossbars 29 and the resulting grille core is enclosed by a frame 30 which is suitably secured to an upstanding flange 31 at the inner edge of the ring 21. Preferably, the sectors stop short of the axis of the opening 25, and these ends are covered by a plate 32 of small diameter, this plate being welded or otherwise suitably secured to the grille sectors.

With the intercepting devices or grilles arranged as above described, it will be apparent that the body of air forced through the opening 25 is divided by the individual grille sectors into the separate streams 26 of corresponding cross-sectional area, each stream being diverted by the 35 inclined grille fins outwardly and along the planes of the fins. Although the latter are disposed at approximately 45 degrees to the horizontal, the angle of discharge of the streams 26 will vary from 30 to 60 degrees, according to the velocity 40 of the air forced through the sectors. By thus separating the air body into a comparatively large number of streams, that is, six in the present instance, rapid mixing with the room air is effected, and a quick reduction in velocity is achieved with 45 a resultant minimizing of drafts on the room occupants, and this even at very short distances from the ceiling, as in the case of the streetcar arrangement illustrated in Fig. 1. This reduction in velocity is due to the large area of the exposed 50 peripheral surfaces of the separated air streams 55

and the increase of this area as the streams progress downwardly.

It has been found that an advantageous looping together of the central streams 26 with the peripheral air stream 9 may be effected by imparting a swirling effect to the moving air body before its discharge through the grilles 27. In the form shown in Figs. 1 and 3, this is accomplished by a rotary fan having a series of angularly spaced blades 35 projecting radially from the shaft 36 of a motor 37, the fan being disposed within the air supply duct 15 a short distance above the central opening 25. The blades are inclined relative to their plane of rotation and, in the form shown in Fig. 1, are used to perform the additional function of delivering air under pressure to both outlets of the unit. This air is drawn inwardly through side openings 38 in a housing 39 that encloses the motor and the upper end of the duct leading to the distribution unit. By imparting a swirling motion to the air before its discharge from the outlet, it has been found that the central streams 26 tend to loop outwardly and unite with the peripheral stream 9 starting almost immediately adjacent the point of discharge from the outlet and continuing progressively until the propelling energy has been substantially dissipated. This action is illustrated by the arrows in Fig. 1. Dissipation of the energy is accelerated as pointed out above by virtue of the large surface areas of the individual streams 26. As a result, the incoming air is dispersed so rapidly and distributed over such a substantial portion of the room that drafts, which would be objectionable to the room occupants, are avoided at very short distances, on the order of a few feet from the point of discharge into the room. The combined outlet is thus well suited for use in streetcars and the like where, as illustrated in Fig. 1, it is desirable to deliver a majority of the incoming air to the seat occupants while avoiding objectionable drafts on these occupants as well as on persons standing in the aisle between the rows of seats. In the unit described above, the air forced through two of the grille sectors 27 will be delivered to the aisle area, but directed longitudinally thereof. The remaining air is divided into two pairs of streams 26 and directed laterally, as shown by the arrows.

The desirable swirling action above described may also be obtained without the necessity of rotating the blades 35. In the form shown in Figs. 4 and 5, the blades, inclined and positioned in the same way as above described, are mounted stationarily, for example, by providing lugs 40 on the blade tips and interfitting these lugs with eyes 41 punched out of the shell 13. In this modification, the swirling action is derived from the motion of the air body itself, the resulting distribution of the air into the room being essentially the same as in the form first described.

I claim as my invention:

1. A unit for distributing air having, in combination, a shell flared at one end and having an air inlet at the other end, a deflector ring adjacent and beyond the flared end of said shell and coacting therewith to form a peripheral outlet between the ring and the shell for discharging part of the air delivered through said shell outwardly, the inner periphery of said ring defining a central outlet alined axially with said shell, a plurality of grille sectors arranged in said central outlet and each comprising a multiplicity of closely spaced substantially flat fins extending along chords of the sectors and inclined relative to the outlet axis to direct the air streams defined by said grille sectors along and outwardly from said axis.

2. A unit for distributing air having, in combination, a shell flared at one end and having an air inlet at the other end, a deflector ring adjacent and beyond the flared end of said shell and coacting therewith to form a peripheral outlet between the ring and the shell for discharging part of the air delivered through said shell outwardly, the inner periphery of said ring defining a central outlet alined axially with said shell, at least three grille sectors arranged in the outermost axial plane of said central outlet and each comprising a series of closely spaced chordal fins adapted to direct the air streams defined by said grille sectors along and outwardly from said axis, and a plurality of angularly spaced fan blades positioned in said shell and operable to impart a swirling action to the body of air flowing therethrough.

3. A unit for distributing air having, in combination, a shell flared at one end and having an air inlet at the other end, a deflector ring adjacent and beyond the flared end of said shell and coacting therewith to form a peripheral outlet between the ring and the shell for discharging part of the air delivered through said shell outwardly, the inner periphery of said ring defining a central outlet alined axially with said shell, at least three grille sectors arranged in the outermost axial plane of said central outlet and each comprising a series of closely spaced chordal fins adapted to direct the air streams defined by said grille sectors along and outwardly from said axis, and a plurality of angularly spaced fan blades positioned in said shell and operable to impart a swirling action to the body of air flowing therethrough.

4. A unit for distributing air having, in combination, a shell flared at one end and having an air inlet at the other end, a deflector ring adjacent and beyond the flared end of said shell and coacting therewith to form a peripheral outlet between the ring and the shell for discharging part of the air delivered through said shell outwardly, the inner periphery of said ring defining a central outlet alined axially with said shell, and at least three grille sectors arranged in said central outlet and each comprising a series of closely spaced chordal fins inclined relative to the outlet axis to direct the air streams defined by said grille sectors along and outwardly from said axis.

5. A unit for distributing air having, in combination, a shell flared at one end and having an air inlet at the other end, a deflector ring adjacent and beyond the flared end of said shell and coacting therewith to form a peripheral outlet between the ring and the shell for discharging part of the air delivered through said shell outwardly, the inner periphery of said ring defining a central outlet alined axially with said shell, and six grille sectors arranged in said central outlet and each comprising a multiplicity of closely spaced substantially flat fins extending along chords of the sectors and inclined relative to the outlet axis to direct the air streams defined by said grille sectors along and outwardly from said axis.

6. A unit for distributing air having, in combination, a shell flared at one end and having an air inlet at the other end, a deflector ring adjacent and beyond the flared end of said shell and coacting therewith to form a peripheral outlet between the ring and the shell for discharging part of the air delivered through said shell outwardly, the inner periphery of said ring defining a central outlet alined axially with said shell, and a plurality of grille sectors arranged in said central outlet and each comprising a multiplicity of closely spaced substantially flat fins extending along chords of the sectors and inclined relative to the outlet axis to direct the air streams defined by said grille sectors along and outwardly from said axis.

7. A unit for distributing air having, in combination, a shell flared at one end and having an air inlet at the other end, a deflector ring adjacent and beyond the flared end of said shell and coacting therewith to form a peripheral outlet

between the ring and the shell for discharging part of the air delivered through said shell outwardly, the inner periphery of said ring defining a central outlet aligned axially with said shell, and a plurality of grille sectors arranged in said central outlet and each comprising a multiplicity of fins extending along chords of the sectors and inclined relative to the outlet axis to direct the air streams defined by said grille sectors along and outwardly from said axis.
